SPRAY NOZZLE

Gaston F. Hollis, St. Petersburg, Fla., assignor of
one-third to Forrest Hoffman, St. Petersburg,
Fla.

Application May 1, 1937, Serial No. 140,081

4 Claims. (Cl. 299—130)

My invention relates to improvements in spray nozzles, the prime object being to provide a nozzle which may be used for general spraying, and adjustable to provide the proper density of spray, from a fine mist to a coarse droopy spray depending on the density desired.

Another object of my invention is to provide a spray nozzle which will deposit the spray solution upon a pre-determined area without a waste of the material.

Spray nozzles often become clogged with sediment from the spray solution, therefor another object of my invention is to provide a nozzle having a means whereby the said sediment may be easily removed without loss of time in disassembling the nozzle.

No doubt other objects and advantages will appear from the following description and claims, when taken in connection with the drawings, wherein,—

Figure 1 is a plan view of my nozzle.

Figure 2 is a longitudinal section, on the line x—x Figure 1.

Figure 3 is a view of the under side of the nozzle.

Similar reference characters refer to similar parts throughout the several views.

The preferable construction of my improved spray nozzle comprises a cylindrical hollow member or handle 'A' threaded at opposite ends and having a projection 2 designed to accommodate and having therein a plunger 3, said plunger having a head portion 4, between the outer end of the projected portion 2 and the plunger head 35 4 is engaged a spring 5 to return the plunger to normal position after it has been pressed downward for a purpose to be hereinafter described. Within said portion 2 suitable packing is provided adjacent to the plunger 3 to prevent leakage of 40 the spray solution. On the outer end of said handle member 'A' is a coupling member 6 by which said nozzle may be connected with the ordinary spray hose connection 7, the usual gasket being used to prevent leakage. Forming a 45 part of said coupling member 6 is a neck portion 9 upon which is mounted, and secured thereto in any suitable manner, a screening member 10 to screen the solution as it enters the nozzle.

Upon the opposite end of said member 'A' is a 50 coupling member 11 by which a hollow tube or nozzle 12 is coupled with the member 'A', a suitable gasket being used to prevent leakage. The coupling end of said member 12 is open and suitably threaded for coupling purpose, the opposite

or outer end 13 is tapered and has a small centrally located aperture 14.

At times during spraying there is an accumulation of sediment from the spray solution in the aperture preventing a free flow of the solution, therefor to facilitate the removal of said sediment, I provide a cleaning wire member 15 the end 16 of which engages the lower end of the plunger 3 at the point 17, thus when the plunger is pressed downward the wire member 15 is moved 10 forward and guided by the sloping surface 18 into the aperture 14 and through it removing any accumulation.

To regulate the density of spray and concentrate upon a pre-determined area without waste, 15 I provide an adjustable member 'B' the aft portion 20 being semi-tubular shaped to permit association with the nozzle member 12, the outer or fore portion 21 being fan shaped and sloped downward and which acts as a further deflector 20 and a spray spreader and the extreme outer edge bent downward at an angle to form a lip 22. The density of the spray being dependent upon the relation of the lip 22 and the sloping portion 21 to the aperture 14, in order to procure 25 proper relationship and provide proper clearance of parts so adjustment can be made, the aft portion 20 is recessed at 23 and 24 the base of recess 23 being sloped 25 at an angle coinciding with the taper 13 of the outer end of nozzle 12 30 thus providing an engaging or resting surface at this point for the member 'B' which is adjusted forward and tipped when a spray other than a mist is desired, the dash lines in Fig. 2, showing the relationship of the member 'B' to the nozzle 35 12 when a very coarse spray is desired, in which case the jetted solution first strikes the sloping fan portion 21 some distance from the lip 22 retarding the force of the spray before striking the lip 22, or adjusted to a position as shown in 40 full lines in Fig. 2, wherein the lip 22 is practically in direct line with the aperture 14 permitting the jetted spray to contact the lip 22 full force creating a fine or mist spray, the recessed portion 24 forming a rear supporting 45 means for the member 'B' on the nozzle 12 and further providing clearance of the portion 20 to permit correct adjustment of the member 'B'.

To concentrate the spraying on a predetermined area and prevent waste the member 'B' 50 is provided with and forming a part thereof downward projecting and curved under sides 26 which act as deflecting members, said side members being rounded at their fore part to a point 27 just behind the lip 22, Figs. 2 and 3, so as not 55

to hinder a reasonable spread of the spray, the aft portion 20 being formed to fit the nozzle member 12 as shown in Figs. 1 and 3 and suitable locking means such as a bolt and wing nut 28 being provided to lock the member 'B' in place on the nozzle member 12 after desired adjustment has been made.

What I claim:—

1. A spray nozzle of the class described, having in combination, a nozzle member, having a connecting means with a spray solution supply, an aperture at its outer tapered end, providing means for jetting of the spray solution, a spray density regulating member extending beyond the forepart of said nozzle and adjustably associated with the nozzle and slideable thereon to regulate the spray density, the tapered portion in combination with a horizontal portion of said nozzle forming a tilting means and a resting surface for the rear portion of said regulating member, which is semi-tubular shaped and has depressed sloping and horizontal portions to provide seating means for said regulating member upon the tapered and horizontal portions of the nozzle, the outer portion of said regulating member being flat, fan shaped, and sloped downward and outward, thereby providing an intermediate deflecting surface for the jetted solution, and the extreme outer edge thereof bent downward forming a lip, which acts as a further spray deflecting means, and the distance of which from the jet end of the nozzle determines the density of the spray, and means to permit concentration of the spray consisting of side lateral portions extending downward from the plane of the fan shaped portion of the regulating member, and locking means for said member upon the nozzle.
2. Means for producing a spray of varied den-

sity and to permit concentration of the spray, wherein a nozzle is provided having at its outer tapered end, an aperture for jetting of the spray solution, a spray regulating member which is slideable and adjustably associated with and securable on and to said nozzle, the outer portion of said regulating member being fan shaped, with downward projected lateral portions, and flat and sloped downward and outward to a downward extended lip at the outer edge of said member, the rear portion having seating means for said regulating member upon the tapered and a horizontal portion of the nozzle simultaneously, to aid in the adjustment.

3. Means for producing a spray of varied density, and to concentrate the spray, wherein a spray regulating member is provided, the outer portion being flat and fan shaped with downward and inward projected side lateral portions, said fan shaped portion sloped downward and outward to a downward extended lip, the rear portion being adapted to be slidably adjustable and seated upon tapered and horizontal portions of a nozzle to produce the desired spray density, and means for locking said regulating member to said nozzle.

4. Means for producing a spray of varied density where a tubular shaped nozzle having a tapered jet end is used, wherein, a density regulating member is provided, having an outward deflecting surface, the rear portion of said member being shaped to be associated with, slideable on and secured to the nozzle, and seating means for said regulating member on the tapered portion and a horizontal portion of the nozzle simultaneously, to aid in the adjustment.
